(57) **CLAIM**

The ornamental design for a fixture as shown and described.

DESCRIPTION

FIG. 1 is a front, right-side and top perspective view of a fixture showing our new design;
FIG. 2 is a front, left-side and top perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is a perspective view of the fixture of FIG. 1 shown in a position of use with environmental subject matter.
The broken lines depict portions of the fixture that form no part of the claimed design.
The additional broken lines in FIG. 9 depict environmental subject matter that forms no part of the claimed design.

1 Claim, 6 Drawing Sheets
